UNITED STATES PATENT OFFICE.

HUGH COLL, OF MILLVILLE BOROUGH, PENNSYLVANIA.

IMPROVEMENT IN STEAM-OPERATED WATER-EJECTORS.

Specification forming part of Letters Patent No. 90,930, dated June 8, 1869.

To all whom it may concern:

Be it known that I, HUGH COLL, of Millville Borough, in the county of Allegheny, and State of Pennsylvania, have invented a new and useful Improvement in Siphon-Pumps; and I do hereby declare the following to be a full, clear, and exact description thereof, reference being had to the accompanying drawing, making a part of this specification, in which—

Figure 1 is a side elevation of my improvement, and Fig. 2 is a sectional view of the same.

Like letters of reference indicate like parts in each.

The nature of my invention consists in the construction of a steam siphon-pump, or water-elevator, having outer and inner pear-shaped hollow heads, so that a jet or current of steam shall elevate water, and discharge it through and from either or both the heads, as herein-after described.

To enable others skilled in the art to make and use my invention, I will proceed to describe its construction and mode of operation.

a is an outer pear-shaped head or globe, cast hollow, and tapering down at one end into an outer discharge-pipe, *b*.

c is a steam-injection pipe screwed into and which is cast on the other or rear end of the head *a*; thence it passes along at or near the middle of the chamber of the head *a* to any desirable distance, provided its forward or discharging end does not extend beyond the mouth of the inner discharge-pipe *e'*. *e* is an inner head or globe, also cast hollow and pear-shaped, having one end tapered down to the form of a pipe or tube, which forms an inner discharge-pipe, *e'*. At its rear or opposite end it is screwed onto the injection-pipe *c*, or otherwise fastened. It may also be cast onto the pipe *c'*. *s s* are inlets, or openings, so made in the inner head *e* that, when it is in position, they will be opposite to or back of the discharging end of the steam-injection pipe *c*, for allowing the inflow of the air and water from the outer head or chamber *a*. *f* is an opening in the bottom of the outer head *a*, into which the induction-pipe *g* opens, for the admission and supply of water. A nut, *i*, may be, if so desired, screwed onto the injection-pipe *c*, outside of the threaded neck *d*, to

fasten it securely in position. *m* is a nozzle of any suitable construction placed on the discharging end of the injection-pipe *c*.

The mode of operation of my improved steam siphon-pump is as follows:

The steam, passing through the injection-pipe *c*, rushes out of the narrowed end or nozzle *m* with great velocity into the inner discharge-pipe *e'*, and thence into and through the outer discharge-pipe *b*.

The force with which the steam passes into and through the discharge-pipes rarefies or exhausts the air in them, which tends to produce a vacuum in the heads or globes *a e*, which vacuum is immediately filled by the water coming up the induction-pipe *g*, and as the air is also expelled from the discharge-pipes *b e'*, the water following to fill up the vacuum thus formed is caught by the flow of steam, and is forced out of the discharge-tubes *b e'*, and a regular current is established, which is kept up by the continuous pressure of the steam.

The advantage of the holes or openings *s s* is that the resistance of the air at the discharging end *e* of the injection-pipe is equalized by the pressure of the air, through the holes *s s*, behind the nozzle *m*, and in consequence of which a regular current is sooner established. Also, as the inner discharge-tube *e'* is much smaller than outer discharge-tube *b*, the steam from the jet *m* rushes through it into the outer discharge-tube *b* with but slightly diminished force, its force having been preserved by the narrowness of the inner discharge-tube *e'*, while at the same time it expels from the inner discharge-tube *e'*, through the outer discharge-tube *b*, the water that enters the holes *s s*, with great force, causing a very rapid current through the outer discharge-tube *b*, which draws along with it the water in the outer head *a*.

The old kind of siphon-pumps, having but one head, can only be used by placing the discharging end *e* of the injection-pipe three-quarters way across the induction-opening *f*, and even then it requires a much greater head of steam than is necessary in my improved siphon, for the steam, coming in contact with such a large body of water as is in the single head of the old siphon, is sooner condensed, and so loses its power.

In my improved siphon only about one-half the amount of steam is required.

The end or nozzle *m* of the injection-pipe *c* may be placed anywhere along inside the inner head *e*, provided it does not go beyond the limits of the outer head *a*, and the inner head may be moved along the injection-pipe *c*, but works more effectually with the openings *s* back of, or opposite to, some part of the induction-opening *f*.

The water may be discharged from the heads *a e*, either through both the discharge-pipes *b e'*, or, by closing up the end *g* of the outer head *a*, through the inner discharge-pipe *e'*, the water being slightly warmed by the last method.

The nozzle *m* may be made by drawing down the end of the injection-pipe *c*.

The desired amount of steam may be admitted by reducing or enlarging the nozzle *m*.

This siphon-pump may be made of iron, or any other suitable material.

The heads are generally cast of iron.

What I claim as my invention, and desire to secure by Letters Patent, is—

The combination of the pear-shaped heads *a* and *e* with the injection-pipe *c*, arranged substantially as and for the purposes hereinbefore set forth.

In testimony whereof, I, the said HUGH COLL, have hereunto set my hand.

HUGH COLL.
